UNITED STATES PATENT OFFICE

THEODORE R. TREIBER, OF CHICAGO, ILLINOIS, ASSIGNOR TO THE TREIBER COMPANY, OF CHICAGO, ILLINOIS, A CORPORATION OF ILLINOIS

CLOSET CONSTRUCTION

Application filed May 11, 1929. Serial No. 362,301.

My invention relates particularly to closets for dwellings and has for its main object the provision of a closet which, by reason of the door construction thereof, is accessible across substantially the entire front or open side thereof, thereby not necessitating space being left in the closet for the entry of a person for putting articles in the closet or taking them out, and which door construction does not interfere with the space of a room, from which access is gained into the closet, any more than does the ordinary conventional door construction of closets.

Another object of the invention resides in the provision of a double closet construction having the above object in view and which is adapted for installation between two rooms, say bed rooms, each closet enclosure being accessible from a respective room.

The above objects and certain other objects, hereinafter appearing, are embodied in the forms of my invention, hereinafter fully described and illustrated in the accompanying drawings, and are effected by certain novel constructions, combinations and arrangements of parts particularly pointed out in the claims.

In the said drawings—

Figure 1 is a front elevation of a closet construction embodying my invention;

Figure 2 is a horizontal section of a double closet construction taken on a line corresponding with the line 2—2 of Figure 1;

Figure 3 is an enlarged partial sectional view on the line 3—3 of Figure 2;

Figure 4 is a vertical section on the line 4—4 of Figure 2;

Figure 5 is an enlarged partial section similar to Figure 4;

Figure 6 is an enlarged partial sectional view on the line 6—6 of Figure 4.

Like characters of reference indicate like parts in the several views.

Referring to the drawings, 1 designates a closet enclosure which is preferably relatively shallow and open at the front or wide side thereof. See Figures 1, 2 and 4. This enclosure is preferably of ceiling height and is divided vertically by a horizontal partition 2

forming a relatively high lower enclosure and a relatively small upper enclosure.

The upper enclosure is shelved, as designated at 3 for the storage of desired articles, and the front of this enclosure is closed by a pair of cooperating doors 4 slidable horizontally in their planes and which are mounted at their lower ends by means of antifriction bearings 5 bearing on suitable tracks 6, the upper ends of these doors having tongue and groove sliding engagements with the enclosure structure, as designated at 7. See Figures 1, 4 and 5.

The lower or main enclosure is provided with two doors 8 and 9 cooperating to close the open front or wide side thereof, each closing substantially one half of the opening. See Figures 1, 2 and 4. The door 8 is vertically hinged, for outward opening movement, as designated at 11, at one of the sides of the front of the enclosure. The door 9 is slidable horizontally in its plane and is mounted on its lower end by means of antifriction bearings 12 bearing on a suitable track 13, the upper end of this door having a tongue and groove sliding engagement with the enclosure structure, as designated at 14. See Figures 4 and 6.

The sliding door 9 is disposed in the same plane as that of the hinged door 8 when the hinged door is closed thereby eliminating any offset therebetween.

In use, the door 8 is first opened to provide access into the lower enclosure at one side thereof, and then if desired the sliding door 9 is moved over into the position occupied by the door 8 when this door is closed to provide access into the lower enclosure at the other side thereof.

Thus it will be observed that the entire lower enclosure is easily accessible without a person entering the enclosure, thereby rendering the entire space of the enclosure conveniently available for storage.

It will be further observed that, there being but one outwardly opening hinged door, the doors do not interfere with the space of the room, from which access is gained into the closet, any more than does the conven-

tional outwardly opening hinged door closet construction.

The interior of the lower enclosure may be fitted with various devices for the storage of articles of clothing or the like, but is preferably fitted as follows.

Vertically spaced pairs of horizontally spaced supports 15 are secured on the inside of one wall of the enclosure adjacent the open side thereof. These supports extend horizontally and are adapted to have hats 16 laid upon each pair thereof or to have hats 17 hung on hook shaped terminals 18 thereof. See Figures 1, 2 and 4.

An intermediately disposed horizontal bar 19 extends within the lower enclosure in parallelism with the front side thereof and is supported on mountings 21 secured on opposite walls of the enclosure. See Figures 1, 2, 3 and 4. Coats 22 or other articles of clothing may be hung from the bar 19 as by means of coat hangers 23. See Figure 4.

Disposed at the rear lower corner of the lower enclosure and extending in parallelism with this corner is a folding shoe rack 24 for the reception of shoes 25, which rack may be folded to a position adjacent the rear wall of the enclosure, as indicated in broken lines in Figure 4, in the event that the rear portion of the floor of the lower enclosure is desired for other purposes.

The double closet construction embodying my invention is as follows, and is advantageous where closets are desired between two rooms, say two bed rooms.

Referring to Figure 2, a pair of the enclosures provided with either of the lower door constructions, herein described, are disposed in substantial alinement corresponding with the planes of the open sides thereof and have their open sides facing oppositely, whereby each enclosure serves a respective room. The sliding doors 9 are disposed for closing the adjacent portions of the open sides of the enclosures in order that the adjacent floor space of the respective rooms be not interfered with or obstructed by the opening of these doors.

Where as shown the far ends of the enclosures are at walls 27 of the rooms extending normal to the plane of the enclosures the hinged doors 8, preferably, have their axes at the far sides of said enclosures in order that they may be opened to positions adjacent said walls where they are out of the way.

Preferably, wall elements 28 are disposed at the rear sides of the enclosures to finish the same corresponding with the room walls.

While I have herein shown and particularly described the preferred embodiment of my invention I do not wish to be limited to the precise details of construction shown as changes may readily be made without departing from the spirit of my invention, but having thus described my invention, I claim

as new and desire to secure by Letters Patent the following:—

Claims:

1. In a closet the combination of an outwardly opening vertically hinged door having its axis disposed at one side of the access opening of the closet and a second door cooperating with said hinged door to close said opening and horizontally slideable in its plane from closed position toward said side of said access opening.

2. In a closet the combination of an outwardly opening vertically hinged door having its axis disposed at one side of the access opening of the closet and a second door disposed in the plane of the hinged door when closed and cooperating therewith to close said opening and horizontally slideable in its plane from closed position toward said side of said access opening when said hinged door is open.

In witness whereof I hereunto affix my signature this 25th day of April, 1929.

THEODORE R. TREIBER.
